BOTTLE NOZZLE

Phoebus Berman, Los Angeles, Calif.

Application January 4, 1935, Serial No. 341

4 Claims. (Cl. 215—79)

My invention relates to bottle nozzles and has particular reference to a device which may be employed to permit simultaneous flow of liquid from a bottle or container and inflow of air to the container.

In extracting liquids from containers, particularly bottles and similar vessels, it is necessary to permit air to flow into the bottle to replace the liquid drawn therefrom in order that the flow of liquid from the bottle or other vessel may be in a steady stream. This is particularly advisable when the liquid is of such nature that air must be prevented from being trapped by the outgoing liquid, such as when the liquid is to be used in treatment of certain diseases by the injection of the same from the container direct into the human body. In the practice of introducing intravenous solutions into patients in the treatment of certain diseases, particular care must be taken not only that the outgoing liquid shall not trap and carry air into the veins of the patient and that the stream of liquid coming from the vessel or bottle shall be steady but also that the air which is employed to replace the contents of the bottle shall be filtered in order to prevent contamination of the contents of the bottle or other vessel.

Various nozzles and devices have been employed to permit steady inflow of air into such bottles or vessels, these devices comprising the attachments which must be placed upon the bottle, and by reason of their intricate construction cannot be readily cleaned and sterilized, and, further, since they attach to and project from the bottle or other vessel, are subject to breakage while the treatment is being given.

It is, therefore, an object of my invention to provide a bottle nozzle which may lie wholly within the bottle or other vessel from which the liquid is to be extracted.

Another object of the invention is to provide a nozzle of the character set forth in the preceding paragraph in which the incoming air is carried through a tortuous path, a portion of which includes a liquid seal through which the air must be filtered.

Another object of the invention is to provide a device of the character set forth herein, in which the air introduced into the bottle is at a higher level than the point of egress of the liquid from the bottle, thus permitting trapping of the air in the outgoing stream.

Another object of the invention is to provide a bottle nozzle of the character set forth, in which the point of introduction of the air into

the bottle or vessel lies at a considerable distance from the point of egress of the bottle, thus further preventing contamination, or trapping, of the air in the outgoing stream.

Other objects and advantages will be apparent from a study of the following specifications, read in connection with the accompanying drawing, wherein

Figure 1 is a diagrammatic view of a bottle or vessel employed for administering intravenous solutions, illustrating my bottle nozzle therein connected to the instruments employed in such treatments;

Fig. 2 is a perspective view of my bottle nozzle located within the neck of a bottle, similar to that shown in Fig. 1, the bottle being illustrated in phantom dotted lines;

Fig. 3 is a development of the exterior of my bottle nozzle, illustrating the air passage and the liquid passage therein; and

Fig. 4 is a sectional view of a bottle nozzle constructed in accordance with my invention, taken along line IV—IV of Fig. 2.

Referring to the drawing, I have illustrated a bottle 1, representative of a bottle, container or other vessel in which liquids may be supplied for intravenous treatments, such bottle being ordinarily provided with a suitable neck 2 leading to an outlet or mouth 3 which, if desired, may be provided with threads or other closure attachments, whereby a cap or other closure may be placed upon the bottle to retain the contents therein. When it is desired to remove the contents from the bottle 1, a tube 4, leading to an injection needle 5, must be attached to the bottle or vessel 1 to communicate with the interior thereof, permitting the liquid therein to flow out through the tube and out through the needle 5.

As will be understood by those skilled in the art, it is necessary that air be introduced into the bottle 1 to replace the liquid which is drawn therefrom through the tube 4, and I provide a bottle nozzle 6 which may be inserted into the neck 2 of the bottle, the particular form of which is preferably as shown in Fig. 2. The bottle nozzle 6 comprises a cylindrical section of rubber or other compressible material which may be inserted into the neck 2 of the bottle to seat tightly in the interior thereof and form a substantial closure for the bottle.

The nozzle 6 is provided with a liquid passage bore 7 preferably extending longitudinally of the nozzle 6 concentrically with the exterior of the cylindrical form thereof so that the liquid is

removed from the central portion of the neck of the bottle 1.

By referring particularly to Fig. 4, it will be observed that the outer end of the liquid bore 7 may be initially sealed by a cap or closure 8 which may be inserted in an enlarged opening 9 at one end of the nozzle 6, or, if desired, the closure 8 may be formed as a thin membrane of the material of which the nozzle is constructed either scored or provided with gripping elements permitting the person using the same to tear out the closure 8 when it is desired to use the nozzle 6.

In order to provide for the admission of air into the bottle 1 while the contents thereof are flowing out through the liquid passage 7, I provide the exterior of the cylindrical form of the nozzle 6 with a long air passage groove 10, one end of which communicates with the exterior of the bottle and the other end of which communicates with the interior of the bottle, the groove being formed in the exterior of the nozzle member 6 so that when the nozzle is inserted in a bottle the interior wall of the bottle will close one side of the passage 10.

By referring particularly to Figs. 2 and 3, it will be observed that the air passage 10 extends from an entrance point 11 as a short, substantially straight passage paralleling the longitudinal axis of the nozzle 6, this portion of the passage terminating in a sharp bend at 12 from which leads a downwardly extending portion 13 communicating with an enlargement 14 of the groove to constitute a liquid trap which, upon inversion of the bottle 1, will partially fill with liquid as indicated at 15, closing the point of communication 16 of the enlargement 14 with the section 13 of the air passage. Thus any air introduced through the entrance 11 will be filtered through the liquid 15 before passing to the interior of the bottle or vessel. From the enlarged portion 14 forming the trap, a relatively small passage 17 extends downwardly to a sharp bend 18 from which a relatively straight portion of the passage extends upwardly, as indicated at 19, to the air outlet 20 in the interior of the bottle.

By referring particularly to Figs. 2 and 3, it will be observed that when the bottle 1 is inverted to allow the contents thereof to pass out, the bend 12 of the passage 10 will lie at a slightly lower level than the point of communication between the liquid trap 14 and the section 17 of the air passage, while, similarly, the entrance 16 of the liquid trap 14 will lie at a slightly lower level than the bed 18 leading to the outlet 20. Thus with but a small amount of liquid 15 in the trap 14 the incoming air must pass through the liquid 15 and there will be little or no tendency for the entire air passage to fill with liquid to siphon off the contents of the bottle. Again it will be noted that by reason of the formation of the air passage 10 at the outer surface of the nozzle member 6, the air outlet 20 at the interior of the bottle is adjacent the interior walls of the bottle, spaced a considerable distance from the liquid outlet passage 7. It will also be noted that the inner end of the nozzle 6 is cut away for half its width in the form of a notch, or recess, 21, the cut-out portion extending over the inner end of the liquid passage 7, thus providing the point of exit of the liquid at a lower level than the point of entrance 20 of the air coming into the bottle or other vessel.

By reason of the respective locations of the inner ends of the air and liquid passages, it will be apparent that the air coming into the bottle

can never be trapped in the outgoing stream therefrom and thus the chance of injecting bubbles of air into a patient is avoided.

It will also be observed that by reason of the construction of the nozzle 6, as illustrated and described herein, the nozzle may be inserted in the bottle by the original manufacturer of the contents thereof, and it will remain in the bottle until it is desired to use the contents therefrom, at which time the outer closure of the bottle may be removed, the tube 14 connected to the liquid passage 7, and the bottle then inverted. This permits of the ready handling of intravenous solutions without contamination thereof by unsterile attachments which would otherwise be required to be placed upon the bottle or vessel. Moreover, by reason of the construction of the nozzle 6 the same is readily adapted to be boiled or otherwise sterilized in any sterilizer without danger of breakage thereof, and without requiring any disassembly of separate parts, as is required in the present-known devices for this purpose.

While I have shown and described the preferred embodiment of my invention, it is to be understood that I do not wish to be limited to any of the details of construction shown herein, except as defined in the appended claims.

I claim:

1. In a bottle nozzle, a nozzle member insertable into the outlet opening of a bottle to completely fill the same, said nozzle member having a tortuous groove extending about the exterior of said member, one end of said groove communicating with one end of said member, the opposite end of said groove communicating with the opposite end of said member, and an enlargement of said groove between the ends thereof constituting a liquid seal through which air passing through said groove will be filtered.

2. An article of manufacture comprising a bottle nozzle having a substantially cylindrical shape and having a groove extending about the exterior of said member constituting an air passage, one end of which communicates with one end of said cylindrical member and the other end of said groove communicating with the opposite end of said cylindrical member, a portion of said groove being enlarged to form a liquid seal through which air must be filtered during its passage therethrough, a recess in one end of said member, and a liquid passage extending longitudinally through said member, one end of which communicates with said recess, and the opposite end of which communicates with the opposite end of said member.

3. An article of manufacture comprising a bottle nozzle member having a shape adapted to fill the outlet opening of a bottle and having a groove extending about the exterior of said member constituting an air passage, one end of which terminates flush with the outer end of said member and the opposite end of said groove terminates flush with the inner end of said member, a liquid passage extending longitudinally through said member from one end to the other thereof, the inner end of said member being recessed at the point of communication of the inner end of said liquid passage whereby the inner end of said liquid passage communicates with the interior of the bottle at a point spaced from the point of communication of the inner end of said groove with the interior of the bottle in the direction of flow of fluid from the bottle.

4. An article of manufacture comprising a bottle nozzle having a substantially cylindrical

shape and adapted to be received in the neck of a bottle, and having a groove extending about the exterior of said cylindrical member constituting an air passage, one end of which communicates with one end of said cylindrical member and the other end of said groove communicating with the opposite end of said cylindrical member, the innermost end of said cylindrical member, when in place in a bottle, being shaped to lie in two

different levels, and the inner end of said groove communicating with the interior of said bottle at one of said levels, and a liquid passage extending longitudinally through said cylindrical member and communicating with said inner end at that level thereof spaced from the level of the end of said groove in the direction of flow of liquid from the bottle.

5 PHOEBUS BERMAN.
